US0D1013577S

(12) **United States Design Patent** (10) Patent No.: **US D1,013,577 S**
(45) Date of Patent: ** *Feb. 6, 2024

(54) **AUTOMOBILE**

(71) Applicant: **BEIJING ELECTRIC VEHICLE CO., LTD.**, Beijing (CN)

(72) Inventors: **Gaowa Wulin**, Beijing (CN); **Xiaokang Zhang**, Beijing (CN); **Heming Zhao**, Beijing (CN); **Liqing Zhu**, Beijing (CN); **Shoujun Wang**, Beijing (CN)

(73) Assignee: **BEIJING ELECTRIC VEHICLE CO., LTD.**, Beijing (CN)

(*) Notice: This patent is subject to a terminal disclaimer.

(**) Term: **15 Years**

(21) Appl. No.: **35/506,006**

(22) Filed: **May 9, 2018**

(80) **Hague Agreement Data**

Int. Filing Date: **May 9, 2018**

Int. Reg. No.: **DM/101657**

Int. Reg. Date: **May 9, 2018**

Int. Reg. Pub. Date: **Nov. 9, 2018**
